Richard D. Oliver,

ATTORNEY

UNITED STATES PATENT OFFICE.

CHARLES W. DAHLMAN, OF CASTLEROCK, WASHINGTON.

WIRE TIE.

1,236,059.

Specification of Letters Patent. Patented Aug. 7, 1917.

Application filed April 12, 1916. Serial No. 90,710.

To all whom it may concern:

Be it known that I, CHARLES W. DAHLMAN, a citizen of the United States, residing at Castlerock, in the county of Cowlitz and

5 State of Washington, have invented certain new and useful Improvements in Wire Ties, of which the following is a specification.

This invention has relation to certain new and useful improvements in wire ties, and 10 has for its primary object the provision of a device of this character which will be of extremely simple construction, composed of the minimum number of parts and which may be applied to a package, empty bags 15 or the like.

The invention has for another object the provision of a wire tie of the above stated character which will be of such construction as to bind securely the opposite ends of 20 the package and retain the separate bags in a flattened condition.

The invention has for a further object the provision of a wire tie of this character which will be composed of the minimum 25 number of parts of simple and cheap construction and which will meet the requirements of the railroad officials in regard to the shipment of empty sacks and the like.

With the above and other objects in view, 30 the invention resides in the novel construction, combination, and arrangement of parts as hereinafter set forth in the specification, pointed out in the claim, and shown in the drawings, in which—

35 Figure 1 is a perspective view of the device in use;

Fig. 2 is a perspective view of the device previous to application of the same to a package.

40 Referring more particularly to the drawings in which similar reference characters designate corresponding parts throughout the several views, 1 designates the horizontal or transverse binding members which 45 have their intermediate portions twisted to form offset loops 2, through which the longitudinal member 3 is threaded.

The transverse binding members 1 are

also bent at one end to form the end loops 4, the ends of the members 1 being twisted 50 around the top portion of the same, as shown at 5.

The longitudinal binding member 3 is also bent at one end to form the end loops 6 and then coiled around the body of the 55 member, as shown at 7. The longitudinal member 3 is threaded through the loops 2 with the transverse binding members 1 in spaced and parallel relation as clearly shown in Fig. 2. The bundle of flattened bags or 60 other articles may then be placed in proper position upon the binding members 1 and 3 and the opposite ends of the transverse binding members 1 bent over and pressed downwardly upon the bags or other articles. 65 The straight ends of the binding members 1 are then passed through the loops 4 and tightened and finally wrapped around the body portions of the binding members 1 as clearly shown at 8 in Fig. 1. The opposite 70 ends of the longitudinal binding members 3 are then bent over the ends of the bags or other articles to be formed into a package, the straight end of the binding member 3 threaded through the loop 6, drawn back 75 to tighten the binding member 3 upon the package and then wrapped around the body portion of the binding member 3 as indicated at 9 in Fig. 3. The package is then completed and may be shipped without danger of articles being lost. 80

While the preferred embodiments of the invention have been shown and described, it will be understood that minor changes in the details of construction, and arrangement 85 of parts may be resorted to within the scope of the appended claim without departing from the spirit of the invention or sacrificing any of the advantages of the same.

What is claimed is:

In a package tie, parallel strands each having one extremity twisted upon itself to provide a loop, the strands being twisted intermediate their ends to provide laterally extending loops which are adapted to lie 95 against the package to be tied, the opposite

extremities of these strands being adapted to be passed around the package and engaged with the first named loops, and a third strand loosely extending through the laterally extending loops and capable of longitudinal movement therein, and having a loop formed upon one of its extremities and its other extremity being adapted

to be passed around the package and engaged with said loop. 10

In testimony whereof I affix my signature in presence of two witnesses.

CHARLES W. DAHLMAN.

Witnesses:

OTTO WEHTJI,
J. A. DEAN.
